United States Patent Office

Des. 179,793
Patented Feb. 26, 1957

179,793

PLASTIC SHEET MATERIAL

Russell Wright, New York, N. Y.

Application March 13, 1956, Serial No. 40,596

Term of patent 14 years

(Cl. D87—3)

Fig. 1a

Fig. 1b

FIG. 2

Figure 1a of the drawing is a plan view showing the left half portion of one repeating unit of the design. Figure 1b of the drawing is a plan view showing the right half portion of one repeating unit of the design. Figures 1a and 1b joined at the broken lines form one complete repeating unit of the design. Figure 2 is another plan view of an enlarged portion of Figure 1a.

I claim:

The ornamental design for plastic sheet material, substantially as shown.
